CLOTHES DRIER

Carl Norman Blaisdell, Somerville, Mass., assignor
to William M. Bass, Lynn, Mass.

Application April 6, 1940, Serial No. 328,280

2 Claims. (Cl. 312—176)

This invention relates to what are sometimes generally referred to as "clothes driers," the invention having particular reference to a rack for use in suspending clothes, and similar articles therefrom particularly for drying the latter.

An object of the present invention is to provide what may be termed an "encased" or housed rack, the invention contemplating the provision of a housing or casing in which the suspension arms of the hanger are housed when the rack is not in use. Thus the hanger will be more easily kept clean, and when not in use will present a more desirable appearance.

The invention together with its objects and advantages will be best understood from a study of the following description taken in connection with the accompanying drawings wherein:

Figure 1 is an elevational view with the parts of the hanger arranged for use.

Figure 2 is a view similar to Figure 1 but with the parts of the hanger arranged as when the hanger is not in use.

Figure 3 is a top plan view of the assembly shown in Figure 1;

Figure 4 is a top plan view of the structure shown in Figure 2.

Figure 5 is a vertical sectional view taken substantially on the line 5—5 of Figure 1.

Figure 6 is a vertical sectional view taken substantially on the line 6—6 of Figure 3.

Figure 7 is a top plan view illustrating a slightly modified form of the invention.

Figure 8 is a detail sectional view taken substantially on the line 8—8 of Figure 7.

Figure 9 is a perspective view of a clamping plate, and

Figure 10 is a sectional view through the clamping plate and carrier plate as assembled.

Referring more in detail to the drawings it will be seen that in accordance with the present invention a casing 5 embodying a back-board or attaching board 6 suitably apertured to accommodate nails or other fastening elements through the medium of which the entire structure may be readily mounted on a wall or similar support.

The casing 5 is closed at the bottom thereof and for the top of the casing there is provided a hinged cover or lid 7, a spring hinge 8 serving to yieldably urge the cover 7 to closed position.

Mounted in the casing 5 are a pair of spaced vertical guide rods 9 which support a vertically shiftable carrier 10. The carrier 10 is in the form of a plate provided at opposite ends thereof with sleeves 11 that have a sliding fit on the rods 9 as shown.

The carrier 10 has extending from one end thereof a finger-piece or handle 12 that works in a suitable slot 13 provided in the wall of the casing 5 and through the medium of which the carrier 10 may be raised or lowered as found desirable.

The carrier 10 has detachably secured thereto a suspension rack, and in the form of the invention shown in Figures 1 to 6, inclusive, the rack indicated generally by the reference numeral 14 comprises a substantially arcuate-shaped frame 15, the ends of which merge into legs 16 that are clamped between the carrier plate 10 and a clamping plate 17, the latter being detachably secured to the carrier plate 10 by bolt and nut means 18. Also at the opposite ends thereof the clamping plate 17 is formed as at 19 to complement the sleeves 11 of the carrier plate.

Pivottally associated with the frame 15 are a plurality of suspension arms 20, the arms being apertured at one end and having the frame 15 threaded therethrough.

When the rack is in use the carrier 10 is pushed upwardly from the dotted line position shown in Figure 5 to the full line position shown in said figure, whereupon the arms 15 are extended upwardly to rest on the upper edge of the wall of the casing 5 with the lid 7 biased by the spring 8 downwardly to engage the pivoted ends of the arms 20 and thus assist the wall of the casing 5 in holding the arms 20 in the horizontal position shown so as to permit garments and the like to be draped thereover.

When not in use the carrier 10 is moved to the retracted or dotted line position shown in Figure 5 causing the arms 20 to move inwardly of the casing 5 to assume the position suggested by broken lines in Figure 5, and thus permitting the cover or lid 7 to assume a fully closed position.

In the form of the invention shown in Figures 7 and 8, the arm-equipped rack therein indicated generally by the reference numeral 14a embodies a plate-like head member 15a that is provided with an arcuate series of notches adjacent the arcuate edge thereof to accommodate the apertured ends of the arms 20a as shown. Head 15a is formed integral with a body plate 16a that is secured between the body plate of the carrier 10 and the clamping plate 17a.

It is obvious that this form of the invention operates substantially in the same manner as does the form above described and illustrated in Figures 1 to 6 inclusive.

In the form of the invention suggested in Figures 9 and 10, there may be used, in lieu of the

clamping plate 17, a clamping plate 21 that is provided at its upper and lower edges with flanges 22 that engage over the upper and lower edges of the plate of the carriage 10, and these flanges 22 are provided with apertures 23 to accommodate the legs 16 of the frame 15 forming part of the rack assembly 14 hereinbefore first described.

From the above it will be seen that I have provided a rack for use in the drying of clothes, various articles, and also for use in a kitchen, bathroom, or the like as a towel rack, which is comparatively simple in construction, easy to operate, and when not in use will be out of the way, and be free, as to appearance and the like, of objections now generally raised against racks of this same general type.

Having thus described the invention what is claimed as new is:

1. In a drier rack of the character described, an attaching plate having a casing mounted thereon and open at its top, a pair of guide rods rising from the bottom of said casing, a carrier slidably associated with said rods, a member mounted on said carrier and movable therewith, a plurality of article-suspension arms pivoted to said member to swing relative thereto to project outwardly of the casing and across the top of the same when in use, and to be moved downwardly

into the casing when the carrier is moved to retracted position and a spring biased hinge cover for the top of the casing and cooperable with the upper edge of the casing for retaining the carrier in elevated position and the arms extending outwardly across the said upper edge of the casing.

2. In a drier rack of the character described, an attaching plate having a casing mounted thereon and open at its top, a pair of guide rods rising from the bottom of said casing, a carrier slidably associated with said rods, a rack member mounted on said carrier and movable therewith, and a plurality of article-suspension arms pivoted to said rack member to swing relative thereto to project outwardly of the casing and across the top of the same when in use, and to extend into the casing when the carrier is in retracted position, said casing having a vertical slot therein and said carrier having a finger piece extending through said slot to facilitate manual manipulation of the carrier, and a spring-biased hinged cover for the open top of said casing and cooperable with the wall of the casing for retaining the carrier in elevated position and the suspension arms extended outwardly with respect to the casing.

CARL NORMAN BLAISDELL.
